UNITED STATES PATENT OFFICE

ARTHUR E. BYRD, OF MILWAUKEE, WISCONSIN, ASSIGNOR TO PHOENIX HOSIERY COMPANY, OF MILWAUKEE, WISCONSIN, A CORPORATION OF WISCONSIN

STOP MOTION MECHANISM FOR KNITTING MACHINES

Application filed January 7, 1929. Serial No. 330,829.

This invention relates to an automatic reset for stop motions utilized with knitting machines or the like.

Various types of stop motions have been heretofore devised for stopping a knitting machine or the like in the event of a thread breaking or knotting in its passage from the bobbins to the needles or in the event of other undesirable conditions existing in the machine. Examples of such stop motions are shown and described in the patents to Crawford, Nos. 1,212,912 of January 16, 1917, 1,354,379 of September 28, 1920, and 1,428,416 of September 5, 1922.

Considerable trouble has been experienced in the use of knitting machines in which manually set or reset stop motions are provided because after the stop motion has operated to stop the knitting machine and the undesirable condition has been removed, the operator starts up the machine and renews its operation without having reset the stop motion. Thus, although the stop motion is on the machine, it is inoperative and ineffective and as a result the machine is liable to be and frequently is injured or damaged and its operation is impaired.

An object of the present invention is to provide for the resetting of the stop motion of a knitting machine or the like automatically whenever the machine is started up or thrown into operation.

Another object of the invention is to provide a resetting mechanism of this character which may be embodied in a simple, compact and unitary structure, which is adapted to be manufactured and installed upon a knitting machine and organized with the stop motion thereof with a minimum of labor and expense, and which is reliable and effective in operation.

As indicated above, the present invention is utilized on knitting machines having the usual stop motion. Such a stop motion controls a sensitive latching mechanism func-

tioning when released to trip a tripping mechanism associated therewith and controlling the action of a second latching mechanism which, when released, permits the throwout of the drive of the machine and the application of the brake usually provided for stopping the machine immediately, when the drive is disconnected. The drive may be a belt drive in which event the second latching mechanism acts when released to permit operation of a belt shifter. Frequently, however, the drive is in a form of an electric motor and clutch controlled gearing so that the second latching mechanism with such a drive operates to permit the throw out of the clutch. The clutch is biased to disengaged position while the brake is biased to engaged position and when the machine is running the second latching mechanism operates to secure the clutch engaged and the brake disengaged. The nature of all constructions of this type heretofore proposed has been such that when the clutch is thrown in and the brake disengaged and these parts are latched in such position it is further necessary for the operator to reach into the machine and manipulate a hand lever for the purpose of setting the tripping mechanism controlled by the first latching mechanism, that is the latching mechanism which is directly operated upon by the stop motion. And in all of these prior constructions, the parts are so constructed and are so coordinated in their movements that the mere act of throwing in the clutch and releasing the brake and latching these parts in position will not reset the tripping mechanism.

The present invention slightly reorganizes the tripping mechanism or means and organizes with the clutch and with the tripping means a resetting device which operates to automatically reset the trip and the first latching mechanism whenever the clutch is thrown into engaged position.

Other objects and advantages reside in cer-

tain novel features of the construction, arrangement and combination of parts which will be hereinafter more fully described and particularly pointed out in the appended 5 claims, reference being had to the accompanying drawings forming a part of this specification, and in which:

Figure 1 is a view in elevation illustrating the automatic reset embodying the present 10 invention applied to a circular knitting machine having a conventional type of stop motion;

Figure 2 is an enlarged fragmentary view in side elevation showing how the automatic 15 reset is organized with the latching mechanism of the stop motion, parts being broken away and shown in section for the sake of illustration;

Figure 3 is a cross sectional view on a line 20 3—3 of Figure 2;

Figure 4 is a fragmentary view in horizontal cross section taken in the plane of line 25 4—4 of Figure 1, parts being omitted and parts being broken away and shown in section for the sake of illustration;

Figures 5, 6 and 7 are cross sectional views all taken on the line 5—5 of Figure 2, but showing the resetting means in various positions;

Figure 8 is a detail view in side elevation of the clutch and brake mechanism and the operating and tripping mechanism therefor, parts being shown in central, vertical, longitudinal section for the sake of illustration;

Figure 9 is a fragmentary view in perspective illustrating the operating and tripping mechanism employed for the clutch and brake of the drive;

Figure 10 is a detail view in section taken 40 on line 10—10 of Figure 8 and showing the brake and its operating means;

Figure 11 is a detail view in elevation showing the operating lever for the brake and associated parts; and

Figures 12 and 13 are detail plan views showing the latching and releasing positions of the latching mechanism of the stop motion.

While, as pointed out above, the present 50 invention resides in the organization, with the usual stop motion, of an automatic reset, it is believed that an understanding of this invention, requires a review of the general structure and operation of the stop motion, the latching mechanism controlled thereby, and the tripping means which is regulated in 55 its action by the latching mechanism and which acts on the clutch and brake or other means governing the drive of the machine.

As shown in Figure 1 of the drawings, reference 60 numeral 1 indicates the frame of a conventional knitting machine which is provided with a knitting head 2 of the ordinary type. The knitting head is driven by an electric motor 3 through the usual gear train 65 which, as shown in Figure 8, includes a con-

stantly driven gear wheel 4 loosely mounted on a shaft 5 although clutched or fixed thereto when desired by a multiple disk clutch 6 of conventional construction. A housing 7 70 completely encloses the gear train and partially encloses the clutch. The shaft 5 has a pinion 8 fixed thereto (see Figure 1) and operating in the usual manner to drive the knitting head 2 when the shaft 5 is rotated.

As indicated, the multiple disk clutch 6 is 75 of conventional construction and as shown in Figure 8 has alternate disks splined to or otherwise constrained to rotate with an annular hub flange 4' integral with the gear 4 and a collar 5' fixed to the shaft 5, respectively. For the purpose of forcing the disks into frictional engagement and thereby clutching the gear 4 to the shaft 5, a slide collar 10 is loosely fitted on the shaft 5 and through a plate 11 also loosely mounted on the shaft 5 controls the compression of springs 12 interposed between the plate 11 and the disks of the clutch. Springs 13 are also provided between the collar 5' of the shaft 5 and the plate 11 and tend to move the plate away from the disks of the clutch 6 thereby relieving the springs 12 of compression and the disks of the clutch of frictional engagement when the slide collar 10 is in 80 clutch releasing position. To shift the slide collar 10 along the shaft 5 and thereby engage or disengage the clutch 6 depending upon the direction in which the collar 10 is moved, a hand lever 14 (see Figures 8 and 9) is provided and is fixed to the upper end of a vertical shaft 15 journaled in a bearing 16 formed on bracket 17 secured to and supported upon a stationary part of the machine. The lower end of the shaft 15 projects below 85 its bearing 16 and is fixed to a yoke 18 which straddles the slide collar and is connected by links 19 to trunnions 10' of the slide collar 10.

When the clutch 6 is disengaged, the machine is instantly stopped by means of a brake provided for the purpose and which as shown in Figures 8 and 10, may comprise a brake drum 20 fixed to the shaft 5 and an internal brake member 21 cooperable with said drum. The brake member 21 is in the form of a split band having the usual friction facing and is biased to expand and engage its drum although it is manually contracted and latched in inoperative position in certain phases of the operation as will hereinafter appear. In carrying out this purpose a conventional brake operating mechanism is employed and as shown in Figures 8, 10 and 11 comprises brake levers 22 and 23 pivoted together as at 22' and cooperable with the ends of the brake band. The lever 23 is pivotally supported adjacent its upper end on a supporting pin 24 carried by the bracket 17 and projecting into the brake drum. An adjusting screw 25 extends transversely between the lower arms 110 of the levers 22 and 23 and passes loosely 115

120

125

130

through openings formed therein. Springs 26 are mounted on the screw 25 and engage abutments on the screw, at least one of which is adjustable, and also engage the levers 22 and 23 so as to bias the levers to expand the brake band into braking engagement with the drum, a stop pin 27 carried by the web of the drum engages the lever 23 to limit its movement in one direction. In order to contract the brake band against the action of the springs 26, a brake operating lever 28 is loosely supported on the pin 24 and has a camming arm 29 integrally formed therewith on one side thereof and engageable with a cam 30 in the form of a closed loop which extends around the pin 24 and which is integrally formed with or fixed to one side of the lever 22 (see Figs. 10 and 11).

When the knitting machine is operating, the clutch is held engaged and the brake is held released, against the action of their respective springs by virtue of the provision of latching means. The latching means for the clutch operating mechanism (see Figs. 4, 8 and 9) comprises an adjustable latch arm 31 fixed to the vertical shaft 15 and engageable with a keeper lever 32 fixed to a vertical shaft 33 supported for rotation in bearings provided therefor on the gear casing and on a bearing bracket 34 fixed to the gear casing. A brake latch lever 35 having the general form of a bell crank is fulcrumed as at 35' on the bracket 17 and has an arm 36 formed with a projection 36' designed to engage a similar projection 28' on the brake operating lever 28. The other arm 38 of the lever 35 is provided with a stop 38a (see Figs. 8 and 9) and a downwardly curved camming portion 38b. The brake is held released by engaging the projection 36' with the projection 28' after the lever 28 has been moved to brake releasing position. This adjustment of the brake is effected after the clutch has been latched in engaged position and consequently the stop 38a on the latch lever 38 engages a brake tripping arm 39 fixed to the shaft 15. The engagement of the stop 38a with the arm 39 is such as to preclude accidental rocking of the lever 35 under the influence of vibration or other similar causes. The parts are so designed that the arm 39 may be in position to engage the clutch when in light contact with the stop 38a. The camming portion 38b of the lever 35 is disposed adjacent the tripping arm 39 in this position of the parts so that when the clutch operating mechanism is released and the arm 39 swings around with the shaft 15, the brake latch lever 35 is automatically released and the brake is applied.

As described, the latch mechanism for the operating mechanism of the clutch and brake is manually set but it is automatically tripped by an appropriate stop motion, one type of which will now be described.

The frame 1 carries a bracket 40 which supports the bobbins 41 (see Fig. 1). The thread runs from the bobbins 41 through eyelets in levers 42 on an upper stop motion 43 and thence through guiding members 44 of the lower stop motion 45 to the knitting head. The stop motions 43 and 45 per se form no part of the present invention and may be of any known form capable of releasing latching mechanism upon the knotting or breaking of a thread. In the construction shown, the stop motions 43 and 45 are connected through suitable motion transmission mechanism in their connecting casing 46 to latching means designated generally at 47 housed by an integral projecting portion 46' of the casing 46 (see Figs. 2, 12 and 13). The design of the stop motions 43 and 45 is such that the latching means 47 will be released by the upper stop motion 43 if any one of the threads passing through the eyelets in the levers 42 becomes knotted or by the lower stop motion 45 if any thread breaks.

The latching means 47 and the mechanism for operating the same in accordance with movement of the stop motions may be of any well known form, the construction shown being a commercial embodiment of that disclosed in Figures 3 to 7 inclusive of the Crawford Patent 1,354,379, referred to above. In this construction, a ring 48 is mounted in the casing 46 (see Fig. 2) and is rotated, a small amount, by mechanism connected to the stop motions 43 or 45 (see Fig. 1) upon the occurrence of a knot or break in a thread. The ring 48 is provided with a pin 48' which engages a trigger 49 on the latching mechanism 47 to trip the same when the ring 48 has been rotated a small amount. The essential elements of the latching mechanism directly controlled by the stop motions are illustrated in Figures 12 and 13 in their released and set positions respectively. The latching mechanisms 47 control a tripping means which functions when set in action by the latching mechanism 47 to disengage the keeper lever 32 from the latch lever 31 and thereby effect release of the clutch 6 and application of the brake.

As more fully disclosed in the Crawford Patents 1,212,912 and 1,354,379, the latching mechanism includes the pivoted trigger 49 (see Figs. 12 and 13) which is biased to operative position and has one end of one of its arms hooked to engage a correspondingly formed end of a slotted arm 50 pivoted as at 50' to a plate 51 secured to the extension 46' of the casing 46. A pin 52 operates in the slot of arm 50 and is carried by a second slotted arm 53 also pivoted to plate 51 as at 53' and operatively connected to a disk 54 by means of a pin 55 carried by the disk 54 and fitted in the slot of the arm 53. The disk 54 is fixed to the upper end of a trip shaft 56 (see Figs. 2 and 4) rotatably supported in

a bearing carried by the plate 51 and biased to tripping position by means of a spring 57. When the trip shaft 56 is turned backwardly from its releasing or tripping position to the position in which it is set or cocked, it winds up the spring 57 and this motion of the tripping shaft 56 also causes the hooked end of the trigger 49 to engage the hooked end of the arm 50 and thus releasably hold the latch mechanism 47 and the trip shaft 56 in set position.

A gear wheel 58 is fixed to the lower end of the shaft 56 (see Figs. 2, 3 and 4). A crank arm 59 is adjustably secured to the gear wheel 58 by means of a screw 59' or any suitable fastening means and at its outer end is provided with a swivel connector 60 having a hole therethrough for receiving and slidably interfitting with one end of a connecting rod 61. Collars 62 and 63 are fixed to the connecting rod 61 for limiting the motion thereof with respect to the connector 60 and a coil spring 64 is interposed between the collar 63 and the connector 60 for urging the connector 60 and collars 62 into engagement while yieldably permitting the rod 61 to slide through the swivel connector.

The other end of the connecting rod 61 is positively though pivotally connected, through a similar swivel connector 65 to a lever 66 fixed to the vertical shaft 33 to which the keeper lever 32 is also fixed as previously described (see Figs. 4 and 9).

A reset actuating arm 67 (see Figs. 4 and 9) is secured to the yoke 18 of the clutch and at its upper end carries a swivel connector 68 to which a connecting rod 69 is adjustably secured, the connecting rod connecting at its opposite end with a device which resets the latching mechanism 47 and the trip shaft 56 automatically at the proper time. The resetting device is shown in detail in Figures 3 to 7, inclusive. As shown, it consists of a pinion 70 rotatably mounted on a stub shaft 45 71 which is fixed to a supporting collar 72 secured to the lower end of the casing extension 46' by set screws 73. The pinion meshes with the bevel gear 58 which as previously described is fixed to the trip shaft 56. Secured to the pinion 70 by means of screws 74 50 75 is a ratchet disk 75 which is provided with a notch 76 on its outer periphery for receiving the pointed end of a pawl 77 pivoted as at 77' on an arm 78 loosely mounted on the shaft 71 and located immediately adjacent the ratchet disk 75. As the pawl 77 is disposed on the side of its arm 78 located flush up against the ratchet disk 75, the pawl 77 is located in the plane of the ratchet disk 60 75. A suitable washer 79 and securing screw 80 are also mounted on the end of the shaft 71 to hold the parts in position (see Figure 3). The lower end of the arm 78 is provided with a swivel connector 81 for receiving the 65 end of the connecting rod 69. A follower 82

is fixed to the pawl 77 by a lock screw 82' and cooperates with a cam 83, formed on a bracket 84 fixed to the collar 72 by screws 72', to raise the pawl 77 out of engagement with the notch 76 in the disk 75 when the cam and follower are in engagement. A spring 85 fixed to the pivot 77 engages a projection on the tail of the follower and biases the pawl 77 to engage the ratchet disk 75 and the follower 82 to coact with its cam 83.

When the machine is running the clutch 6 is, of course, engaged and the brake band 21 is disengaged from the drum 20 and these parts are latched in such positions, the keeper lever 32 engaging the latch arm 31 to hold the clutch engaged and the brake latch lever 35 engaging the brake operating lever 28 to hold the brake released. Further at this time the latching mechanism 47 is in the position shown in Figure 13, that is, with the hook end of the trigger 49 engaged with the hook end of the arm 50. This holds the trip shaft 56 against rotation and at this time the trip shaft is so positioned that its crank arm 59 has moved away from the collar 62 and placed spring 64 under compression, whereby the keeper lever 32 is firmly held and engaged with the latch arm 31. In this position of the parts, the reset is positioned as shown in Figure 6. If the thread knots or breaks, the stop mechanism is set into motion and the pin 48' of the ring 48 disengages the trigger 49 from the arm 50. This releases the trip shaft 56 for rotation and the springs 57 and 64 immediately act, the spring 57 unwinding and rotating the trip shaft 56 and spring 64 expanding and forcing the arm 59 toward the collar 62. Thus the springs 57 and 64 both act to rotate the trip shaft 56 in the initial phase of this operation although the spring 64 ceases to act to rotate the shaft 56 or to move the crank arm 59, after the crank arm has engaged the collar 62. But the combined action of the springs imparts a forcible movement of the connecting rod 61 to the right as viewed in Figure 4 and consequently pulls the keeper lever 32 away from the latch arm 31 thereby releasing the shaft 15 and permitting the springs 12 and 13 to disengage the clutch. The rotation of the shaft 15 swings the arm 39 with it so that the arm 39 coacts with the camming end 38b of the brake latch lever 35 to release it and permit the brake springs to apply the brake. The disengagement of the clutch is accomplished by the sliding of the collar 10 to the left as viewed in Figures 4 and 8 and the clutch yoke 18 partakes of this movement and carries with it the reset actuating arm 67 which in turn pulls the connecting rod 69 to the left as viewed in Figures 4 to 9 inclusive whereby the arm 78 is moved into the position shown in Figure 5. At practically the same instant, the disk 75 is moved to the position shown in Figure 5 since it is fixed to the pinion 70 and the pin 125

ion 70 is meshed with the gear wheel 58 fixed to the trip shaft 56 and rotated thereby. Consequently when the arm 78 moved to the position shown in Figure 5 the pawl 77 carried by the arm 78 snaps into the notch 76 as in such position the follower 82 carried by the pawl is free of the fixed cam 83. The spring 85 acts through the follower 82 to yieldably hold the pawl 77 engaged with its ratchet disk 75. There is now a complete motion transmission train between the clutch operating mechanism and the trip shaft 56 since the pawl 77 is spring pressed into its notch and the frictional engagement is such 10 as to provide an operative connection effective to transmit the relatively light force required. In other words, this mechanical train is such that when the clutch is thrown into engaged position to start the machine, the trip shaft 56 is turned to such extent that its spring 57 is wound up and the latch mechanism 49 engaged. This will be apparent from consideration of Figures 2 to 9 inclusive. To engage the clutch the lever 14 is 20 turned in a counterclockwise direction as viewed in Figures 4 and 9 until its latch arm 31 comes to the position shown in these figures. This, of course, swings the clutch operating yoke 18 to the right as viewed in Figure 9 and causes the reset actuating arm 67 to partake of the corresponding motion. The reset actuating arm 67 pushes the connecting rod 69 to the right as viewed in these figures and this connecting rod 69 in turn 30 rotates the arm 78 from the position shown in Figure 5 to the position shown in Figure 6. At the beginning of this motion of the arm 78 it is connected to the disk 75 by the pawl 77 so that the disk 75 and pinion 70 are constrained to move with the arm 78. After the 40 disk 75 and pinion 70 have been turned through such an angular distance that the pinion 70 acting through the gear wheel 58 has rotated the trip shaft 56 to the extent necessary to wind up its spring 57 and re-engage its latch mechanism 47, the arm 77 is 45 disengaged from the notch 76 of the disk 75 by the action of the follower 82 and cam 83 (see Figure 6) whereby the reset is released from the latching mechanism 47 control by 50 the stop motion so that the effectiveness of the stop motion will not be impaired. As illustrated in Figure 6, the movement imparted by the pawl 77 to the disc 75 is slightly in 55 excess of that required due to clearance and lost motion occurring in the motion transmission train. After the pawl 75 is released the parts readjust themselves under the action of the springs 57 and 64 to the position shown in Figure 7. When the operator moves the 60 lever 14 to throw in the clutch the connecting rod 69 is simultaneously moved and as a result the gear wheel 70 is rotated. The gear wheel 70 being meshed with the gear wheel 58 turns the latter and the rotation of the

gear wheel 58 is transmitted through the connecting rod 61 to the latch 32 to position it to engage the latch member 31.

In other words, whenever the clutch is thrown in, the tripping means and latching mechanism immediately associated with the stop mechanism are automatically reset and as soon as the reset has accomplished this purpose it is automatically disconnected from the parts which it has reset. However, when the stop motion operates to stop the machine the reset is automatically thrown back into operative engagement or into operative condition so that it will again be positioned to function when the operation of the machine is resumed.

The invention claimed is:

1. In a knitting machine, a drive, a control operable to throw in the drive and start the machine, means for releasably holding the control in position to maintain the drive effective to operate the machine, a stop motion operable upon the occurrence of undesirable conditions in the machine, a tripping element operating, when set in action by the stop motion, to release said means and thereby stop the machine, a ratchet element geared to the tripping element, a pawl cooperable with the ratchet element, means actuated by the control for operating the pawl for causing it to drive the ratchet element and impart resetting movement to the tripping element when the control is operated to start the machine, and means for automatically disengaging the pawl from the ratchet element upon completion of the resetting.

2. In a knitting machine, a drive, a control operable to throw in the drive and start the machine, means for releasably holding the control in position to maintain the drive effective to operate the machine, a stop motion operable upon the occurrence of undesirable conditions in the machine, a tripping element operating, when set in action by the stop motion, to release said means and thereby stop the machine, a ratchet element geared to the tripping element, a pawl cooperable with the ratchet element, means actuated by the control for operating the pawl for causing it to drive the ratchet element and impart resetting movement to the tripping element when the control is operated to start the machine, and a cam for disengaging the pawl from the ratchet upon the completion of the resetting movement, said pawl and ratchet being automatically reengaged when the stop motion has operated to stop the machine.

3. In a knitting machine, a drive, a control operable to throw in the drive and start the machine, means for releasably holding the control in position to maintain the drive effective to operate the machine, a stop motion operable upon the occurrence of undesirable conditions in the machine, a tripping element operating, when set in action by the stop

- motion; to release said means and thereby stop the machine, a resetting element geared to the tripping elements, and motion transmission means between the control and the resetting element including a one-way driving connection effective, when the control is actuated to start the machine, to impart operative movement to the resetting element, but automatically freeing the resetting element after resetting.
4. In a stop motion for knitting machines or the like, the combination of latching mechanism and a setting device therefor, said latching mechanism including a rotary element, means for latching said element when it has been rotated a predetermined amount in a given direction, and means for releasing said latching means upon the occurrence of undesirable conditions in the knitting machine, said setting device including an element associated with the rotary element of said latching mechanism and constrained to rotation therewith, ratchet means for rotating said element in one direction and means for releasing said ratchet means when the element has been rotated sufficiently to permit such latching means to engage the rotary element of said latching mechanism.
5. In a stop motion for knitting machines or the like, the combination of a latching mechanism and a setting device therefor said latching mechanism including a movable element, means for latching said element when it has been moved a predetermined amount in a given direction, and means for releasing said latching means upon the occurrence of undesirable conditions in the knitting machine, said setting device including an element associated with said latching mechanism and constrained to movement therewith, means for moving said element in one direction and means for releasing said moving means when the element has been moved sufficiently to permit said latching means to latch the movable element of said latching mechanism.
6. In a knitting machine, in combination, a drive, a control adapted to be set to render the drive effective, means for releasing the control to disconnect the drive and stop the machine upon the occurrence of undesirable conditions in the machine and including a stop motion and latching and tripping mechanism controlled thereby, and a resetting device for the latching and tripping mechanism, comprising a gear connected to the latching and tripping mechanism, an actuating element receiving its motion from the control, and motion transmission means between the actuating element and the gear.
7. In a knitting machine, in combination, a drive, a control adapted to be set to render the drive effective, means for releasing the control to disconnect the drive and stop the machine upon the occurrence of undesirable conditions in the machine and including a stop motion and latching and tripping mechanism controlled thereby, and a resetting device for the latching and tripping mechanism, comprising a gear connected to the latching and tripping mechanism, an actuating element receiving its motion from the control, and motion transmission means between the actuating element and the gear.
8. A resetting device for a stop motion of a knitting machine having the usual drive control and the usual tripping shaft and comprising a resetting element adapted to be geared to the trip shaft, an actuating element adapted to be connected to the control and motion transmission means between the actuating and the resetting element and including a one-way driving connection.
9. A resetting device for a stop motion of a knitting machine having the usual drive control and the usual tripping shaft and comprising a gear wheel fixed to the tripping shaft, a pinion meshed therewith, a ratchet element fixed to the pinion, a pawl carrier mounted for rotation relative to the pinion, a pawl mounted on said carrier and cooperative with the ratchet element, a connecting rod between the drive control and the pawl carrier, and means for automatically disengaging the pawl from the ratchet element upon the completion of the resetting.
10. A resetting device for a stop motion of a knitting machine having the usual drive control and the usual tripping shaft and comprising a gear wheel adapted to be fixed to the tripping shaft, a pinion meshed with said gear wheel and means adapted to be actuated by the drive control when the same is manipulated to start the machine and acting to rotate the pinion to effect resetting.
11. In a knitting machine, a drive, a control operable to throw in the drive and start the machine, means for releasably holding the control in position to maintain the drive effective to operate the machine, a stop motion operable upon the occurrence of undesirable conditions in the machine, a tripping element operating, when set in action by the stop motion, to release said means and thereby stop the machine, resetting means actuated by the control, a releasable connection between the resetting means and the tripping element and stop motion and automatically completing a motion transmission train between the resetting means and the tripping element and stop motion under the influence of the control and the stop motion when the control is positioned to stop the machine by

virtue of the action of the stop motion, and means for releasing said releasable connection and disconnecting the stop motion and tripping element from the resetting means
5 after the control has been thrown to position to start the machine and the stop motion and tripping element have been reset by the resetting means.

In witness whereof, I have hereto affixed
10 my signature.
